HAMMER MECHANISM

John C. Garand, Springfield, Mass.

Application August 21, 1943, Serial No. 499,443

9 Claims. (Cl. 42—69)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a hammer mechanism for a firearm.

It has long been appreciated in the firearm design that the most preferable type of hammer blow is delivered by a hammer having a large spring force exerted on the hammer immediately prior to striking the firing pin of the firearm. However, it is most undesirable to the functioning of reciprocating bolt type firearms, and particularly those utilizing the rotary movement of a bolt to accomplish locking, to have the hammer exerting a considerable force against the rear end of the bolt immediately after discharge of the cartridge and during the initial movement of the bolt.

Hammer designs heretofore known in the art resulted in a compromise between the foregoing desirable and undesirable features and resulted in a rebounding type hammer where the hammer spring is permitted to exert a substantial force on the hammer until the hammer reaches a position slightly short of its position of impact with the firing pin. In this position the spring force is arrested and the velocity already imparted to the hammer is sufficient to produce an impact blow on the firing pin with the necessary amount of energy. In such constructions the hammer can then rebound after striking the firing pin to the point where it again is in contact with the hammer spring. This type of design thus produces a hammer which has no biasing force exerted on it in its position immediately adjacent to the firing pin. As will be recognized by those skilled in the art this condition is also undesirable since a light bias, on the order of several pounds, should be maintained on the firing pin during the discharge of the cartridge in order to prevent the primer of the cartridge from blowing out. This also results in the recoiling bolt striking the hammer an impact blow with resultant decrease in life of the parts.

Accordingly, it is an object of this invention to provide an improved hammer mechanism.

It is a particular object of this invention to provide a hammer mechanism wherein a large spring force is exerted on the hammer until it reaches the position immediately adjacent the firing pin and thereafter a light spring bias is exerted on the hammer.

The specific nature of this invention as well

as other objects and advantages thereof will clearly appear from a description of a preferred embodiment as shown in the accompanying drawing in which:

Fig. 1 is an enlarged detail view of the hammer and trigger mechanism partly in section showing the hammer in the forward or released position.

Fig. 2 is a side elevational view of the hammer plunger.

Fig. 3 is a top elevational view of Fig. 2 partly broken away to show the auxiliary hammer spring and plunger.

Fig. 4 is an enlarged right end view of Fig. 2.

Referring to Fig. 1, there is shown one modification of this improved hammer design wherein the hammer and trigger elements are mounted on a trigger frame 1. The trigger frame 1 comprises a base portion 2, a front upstanding portion 3, a rear upstanding portion 4, and a side wall 5. A trigger 6 is pivotally mounted on a transverse pin 7 which is supported in suitable holes in the rear upstanding portion 4 and side wall 5 of the trigger frame 1. The trigger 6 comprises a lower portion 8 conventionally shaped for engagement by the finger of the operator and an upper sear portion 9 having transversely projecting locking lugs 10. A hammer 11 has its one end pivotally mounted on a pin 12 which is journaled in the front upstanding portion 3 of the trigger frame 1. The hammer 11 has a head portion 13 suitably shaped to engage a firing pin (not shown) and a rearward bifurcated sear engaging extension 14 provided with locking shoulders 14a. When the hammer 11 is pivoted to the rear, or to the left, as viewed in Fig. 1, as it would be by a bolt of a firearm riding back over it in the conventional manner, the locking extensions 10 of the sear portion 9 of trigger 6 engages the locking shoulders 14a of the sear engaging extension 14 of the hammer and hold the hammer in a cocked position.

A hammer spring 15 is mounted to operate between the hammer and the trigger 6. The hammer spring 15 is partially enclosed in a spring housing 16, which housing terminates in a pair of bifurcated lugs 17. A transverse hole 18 is provided through the pair of bifurcated lugs 17 by means of which the housing 16 is mounted on the pin 7. In this position the bifurcated lugs 17 surround the central portion of the trigger 6. It should be mentioned that the hole 18 through the bifurcated lugs 17 is substantially larger than the diameter of the pin 7 thereby permitting a cam portion 19 on the front of the

central portion of the trigger 6 to engage that portion of the housing 16 lying between the legs of the bifurcated lug 17 and receive the force exerted by the hammer spring 15. Thus a force is supplied to oppose pulling of the trigger.

The hammer spring 15 surrounds a plunger 20 having an enlarged head portion 21 which has a nose 22 shaped to engage a notch 23 in the hammer 11. A transverse extension 24 of the head 21 of the plunger 20 rides in a slot 25 provided in the side wall 5. This slot stops the movement of the plunger 20 under the force of the spring 15 when the hammer 11 reaches a point just short of its point of impact with the firing pin (not shown). Slightly beyond this point, the hammer would be stopped by engagement of its front surface 26 with upstanding portion 3 of the trigger frame 1. It would therefore be apparent that so far as the hammer spring 15 is concerned, there is a limited range of pivotal movement of the hammer in the region adjacent to its position of impact to the firing pin where no bias is exerted on the hammer by the hammer spring. Thus the hammer will yield the desirable characteristics of the rebounding type.

To provide a light bias on the hammer in this position, a recess 27 is provided in the head end of the plunger 20. In this recess an auxiliary spring 28 and an auxiliary plunger 29 is mounted. Plunger 29 has a head end 30 shaped to engage the notch 23 of the hammer 11. Thus a light biasing force is exerted on the hammer by auxiliary plunger 29 after the hammer reaches the end of slot 25 in side wall 5 and passes the position where the transverse extension 24 of the plunger 20 prevents the hammer spring 15 from acting further on the hammer as illustrated in Fig. 1. The spring 28 is much lighter than hammer spring 15 hence during the cocking movement of the hammer, the end 30 of auxiliary plunger 29 is flush with the head portion 21 of plunger 20, permitting the load to be carried by the larger plunger 20.

It will therefore be apparent that this invention provides a rebounding type hammer wherein a spring force of substantial magnitude is continuously exerted on the hammer up to the position just short of its position of impact to the firing pin. From that position to the point of impact of the firing pin only a light bias is exerted on the hammer which insures that the primer of the cartridge will not blow out under the pressure developed by the discharge of the cartridge.

I claim:

1. In combination, a pivoted hammer movable thru a limited arc, a spring biased plunger engaging said hammer and exerting a force thereon thru all but one extreme portion of said hammer's pivotal movement and an auxiliary spring biased plunger operating between said hammer and said plunger irrespective of the position of said hammer.

2. In combination, a pivoted hammer movable thru a limited arc, a spring biased plunger engaging said hammer and exerting a force thereon thru all but one extreme portion of said hammer's pivotal movement and an auxiliary spring biased plunger mounted in said first mentioned plunger, said auxiliary plunger engaging said hammer and exerting a force thereon continuously, irrespective of the position of said hammer.

3. In combination, a pivoted hammer movable thru a limited arc, a spring biased plunger engaging said hammer and exerting a force thereon

thru all but one extreme portion of said hammer's pivotal movement and a recess in the end of said plunger engaging the hammer, an auxiliary plunger mounted in said recess and an auxiliary spring mounted behind said auxiliary plunger, said auxiliary spring biasing said auxiliary plunger against said hammer in all positions of said hammer.

4. In a firearm having a firing pin, a pivoted hammer arranged to strike the firing pin and a spring biased plunger for operating the hammer, the improvement comprising means for stopping the movement of said plunger at a point prior to the point of impact of the hammer on the firing pin, an auxiliary plunger movably mounted in the head of said first mentioned plunger and a spring biasing said auxiliary plunger into engagement with said hammer whereby a bias is exerted on said hammer by said auxiliary plunger in all positions of said hammer.

5. A hammer mechanism comprising a frame, a hammer pivotally mounted on said frame for movement thru a limited arc, a spring housing pivotally mounted in said frame, a hammer spring mounted in said spring housing, a plunger biased by said spring into engagement with said hammer, means on said frame cooperating with said plunger to limit the movement of said plunger so that said plunger does not engage said hammer during the extreme portion of said hammer's pivotal movement and resilient means mounted between said plunger and said hammer, said resilient means exerting a bias on said hammer irrespective of the position of said hammer.

6. A hammer mechanism comprising a frame, a hammer pivotally mounted on said frame for movement thru a limited arc, a spring housing pivotally mounted in said frame, a hammer spring mounted in said spring housing, a plunger biased by said spring into engagement with said hammer, means on said frame cooperating with said plunger to limit the movement of said plunger so that said plunger does not engage said hammer during the extreme portion of said hammer's pivotal movement, a spring biased auxiliary plunger mounted in said first mentioned plunger, said auxiliary plunger engaging said hammer and exerting a force thereon continuously, irrespective of the position of said hammer.

7. A hammer mechanism comprising a frame, a hammer pivotally mounted on said frame for movement thru a limited arc, a spring housing pivotally mounted on said frame, a hammer spring mounted in said spring housing, a plunger biased by said spring into engagement with said hammer, said frame having a slot adjacent the said plunger, a transverse projection on said plunger engaging in said slot, said slot limiting the movement of said plunger so that said plunger does not engage said hammer during the extreme portion of said hammer's pivotal movement and resilient means mounted between said plunger and said hammer, said resilient means exerting a bias on said hammer irrespective of the position of said hammer.

8. A hammer mechanism comprising a frame, a hammer pivotally mounted on said frame for movement thru a limited arc, a spring housing pivotally mounted on said frame, a hammer spring mounted in said spring housing, a plunger biased by said spring into engagement with said hammer, said frame having a slot adjacent the said plunger, a transverse projection on said plunger engaging in said slot, said slot

limiting the movement of said plunger so that said plunger does not engage said hammer during the extreme portion of said hammer's pivotal movement, a spring biased auxiliary plunger mounted in said first mentioned plunger, said auxiliary plunger engaging said hammer and exerting a force thereon continuously, irrespective of the position of said hammer.

9. A hammer mechanism comprising a frame, a hammer pivotally mounted on said frame for movement thru a limited arc, a spring housing pivotally mounted on said frame, a hammer spring mounted in said spring housing, a plunger biased by said spring into engagement with said

hammer, said frame having a slot adjacent the said plunger, a transverse projection on said plunger engaging in said slot, said slot limiting the movement of said plunger so that said plunger does not engage said hammer during the extreme portion of said hammer's pivotal movement, a recess in the end of said plunger engaging the hammer, an auxiliary plunger mounted in said recess and an auxiliary spring mounted behind said auxiliary plunger, said auxiliary spring biasing said auxiliary plunger against said hammer in all positions of said hammer.

JOHN C. GARAND.
